UNITED STATES PATENT OFFICE.

VICTOR CARL JOHANSSON, OF LONG ISLAND CITY, NEW YORK.

SUPPORTING DEVICE.

Application filed July 23, 1928. Serial No. 294,904.

The present invention relates to improvements in supporting or suspension devices and has for its principal object to provide a structure that may be attached to walls, 5 ceilings, or the like, for suspending a plurality of independently movable carriers, each of which has associated therewith a suspension hook.

The prime object of the invention is to 10 provide a supporting structure of the above mentioned character that is designed more especially for use beneath the shelves in a closet, whereby coffee and tea cups may be supported in a suspended manner in a row 15 beneath the shelf.

A further object is to provide a supporting device of the above mentioned character wherein each of the carriers is formed with a means for receiving a block to which the 20 shank of the suspension hook is attached, the block being arranged in each carrier in such a manner as to permit the hook to be positioned in any predetermined direction prior to the disposition of the carrier within 25 the stationary track member.

A further object is to provide a supporting device of the above mentioned character that includes complementary means 30 between the stationary track and the independently movable carriers, whereby said carriers may be supported in the track member in a frictional manner against casual movement, the carriers being inserted and removed with respect to the stationary track 35 from either end thereof.

A further object is to provide a supporting device of the above mentioned character which is simple in construction, inexpensive, 40 strong and durable, and further well adapted to the purpose for which it is designed.

Other objects of the invention will become apparent as the nature of the invention proceeds and when taken in connection with the accompanying drawings.

In the accompanying drawings, forming a part of this application, and wherein like reference characters designate like parts throughout the views:

Figure 1 is a fragmentary side elevation 50 of the supporting device embodying my invention, showing the same attached to the bottom face of a shelf.

Figure 2 is a sectional view, taken approximately on the line 2—2 of Figure 1.

Figure 3 is a sectional view, taken approximately on the line 3—3 of Figure 2.

Figure 4 is a fragmentary detail perspective view of one end portion of the stationary track unit.

Figure 5 is a detail perspective view of 60 one of the carriers.

Figure 6 is a detail perspective view of one of the hooks and the block carried by the shank thereof, and

Figure 7 is an elevational view of one of 65 the hooks, showing the manner in which the block is secured on the end of the shank.

In the drawings, wherein for the purpose of illustration is shown the preferred embodiment of my invention, the numeral 1 70 designates generally the stationary track unit that is adapted to extend longitudinally beneath a support, such as the shelf in a closet and which shelf is denoted by the letter A in Figure 1. The track 1 is of such 75 length as to terminate inwardly of the respective ends of the shelf to facilitate the ready insertion and removal of the independent carriers and the hooks associated therewith, as suggested in Figure 1.

The track unit consists of a strip of metal 80 that is so bent as to form a top portion 2, which top portion constitutes the intermediate portion of the strip while the longitudinal edge portions of said strip are bent 85 back beneath the top portions as at 3 and 4 respectively, the longitudinal free edges of the strip being slightly spaced with respect to each other, to form a longitudinally extending guide slot 5, as shown in Figures 2 90 and 4 of the drawings, and the purpose of which will be presently described. The bends are slightly rounded as indicated at 6, while the top forming portion 2 is so constructed at its longitudinal central portion 95 as to form a substantially inverted channeled portion 7, the base of which is formed with openings 8 to accommodate fastening screws 9 that are driven into the bottom of the support A as clearly indicated in the 100 drawings.

The channeled portion 7 extends for the full length of the strip and as is clearly suggested in Figure 2, the portions of the top 2 gradually bulge upwardly from the respective sides of the inverted channeled portion to the bends 6.

The invention further comprehends the provision of a plurality of carriers, such as is shown at 10, in Figure 5, and each carrier 110 comprises a rectangular shaped strip of spring metal, the end portions of which are

rolled back upon themselves to form inturned beads or lips 11, that frictionally engage within the respective bends 6 formed in the stationary track unit 1, as shown in Figure 5 2. The body portion 12 of each carrier has formed in its center a rectangular shaped depressed socket forming portion 13, that will slidably fit between the longitudinal free edges of the track 1, for operation in the guide 10 slot 5, as also suggested in Figure 2, and an opening 14 is formed in the bottom of this socket 13, as clearly shown in Figure 5.

The invention further comprehends the provision of an article suspension hook 15 15 that has its shank 16 formed with a head 17, on its free end, and this shank has its free end portion embedded rigidly within a rectangular shaped block 18, so that the blocks and the hooks will constitute a unitary 20 structure. It is of course, to be understood that the block 18 is not attached to the headed end of the shank, until said shank has been disposed upwardly through the opening 14 in the depressed socket 13 of each carrier, 25 and the block is of such size as to snugly fit within the socket 13, and in this manner, the carrier and the hook will form a unitary structure, that is to say the hook cannot be removed from the carrier, but is capable of 30 being positioned so that the hook may face either the front or back or either side by raising upwardly on the hook, to disengage the block from its socket and then by turning the hook to the desired position and again 35 lowering the same until the block enters the socket again, as is shown in Figure 2, and when the block is positioned in the socket, the hook cannot turn with respect to the carrier.

40 In the present instance, the support is utilized for supporting tea cups or coffee cups in a closet, and any number of these slidable carriers 10, together with the hooks carried thereby can be positioned in the track unit 1, by sliding the same in said track from either 45 end, and the carriers may be independently moved when positioned in the track unit for properly spacing the same with respect to each other.

50 When the parts are arranged as shown in Figure 1, a cup can be readily and easily attached or removed from any one of the hooks, without necessitating the removal of the carrier and its hook from the track unit, and due 55 to its simplicity, the supporting device can

be readily and easily attached, and when in position will not necessitate any adjustment. The depressed socket 13 will move along within the guide blocks 5 while the blocks 18 will operate in the inverted channeled portion 7 60 and the inturned lips or beads 11 will frictionally engage with the inner faces of the bends 6, so that the carriers cannot be casually removed or displaced from the track unit, but are capable of manual manipulation 65 either to remove the carrier from the track unit or for adjusting the same when positioned in the track unit.

The use of a supporting device of the above mentioned character, will obviate the necessity of having to form a series of holes in the bottom of the shelf for attaching the cup supporting hooks, as must now necessarily be done with the type of cup suspension hooks now in use. Furthermore, a structure of this 70 character may be manufactured at a very low cost, and the same will, at all times, be positive and efficient in carrying out the purposes for which it is designed.

75 While I have shown the preferred embodiment of the invention, it is to be understood that various changes in the size, shape and arrangement of parts may be resorted to, without departing from the spirit of the invention or the scope of the appended claim.

80 I claim:

85 In a device of the class described, the combination of a suspension hook provided with a upwardly disposed shank, a non-circular head carried by the upper end of the shank, a 90 track unit adapted to be secured to a support, said track unit including a top, sides and a bottom, the bottom being formed with a longitudinal slot, the intermediate portion of the top being bent to provide an inverted 95 channel, a carrier adapted for removable and slidable disposition within the track unit, said carrier including a body portion having its ends bent for frictional engagement with the respective sides of the track unit, a non-circular socket forming portion arranged in the body of the carrier for disposition within the longitudinal slot in the bottom of the track 100 unit, the shank of the hook extending upwardly through the socket, said non-circular head being adapted for disposition within the socket and also operable within the inverted channeled portion.

105 In testimony whereof I affix my signature.

VICTOR CARL JOHANSSON.
